REEL AND A METHOD OF FORMING IT

Paul S. McCann, La Grange, Ill., assignor to
 Western Electric Company, Incorporated, New
 York, N. Y., a corporation of New York

Application September 27, 1934, Serial No. 745,658

5 Claims. (Cl. 242—77)

This invention relates to reels and a method of forming them and more particularly to metallic reels for supporting material susceptible of being wound thereon and a method of forming them.

5 It is an object of the present invention to provide an inexpensive, strong and durable metallic reel having a low weight consistent with its strength and an improved method of forming reels.

10 In accordance with one embodiment the invention contemplates the provision of a reel composed of a pair of metallic heads, each comprising a plurality of segments formed from rectangular sheets of metal corrugated transversely in such a manner as to bring the sheet around into the form of an annulus, the corrugations being deeper in the direction of the thickness of the sheet at the inner edge of the annulus than at the outer edge thereof to use the excess metal 20 and make the head thicker at the inner portion thereof so as to strengthen the head at the point of greatest stress. A pair of circular channel members with their flanges extending inwardly are welded to the inner and outer edges of the 25 annulus to provide means for fixing a drum to the inner edge and to provide a smooth outer surface for the head to which lagging may be attached.

Other novel features and advantages will be 30 come apparent in the following detailed description when considered in conjunction with the accompanying drawings, wherein

Fig. 1 is a side elevational view of a reel which is a preferred embodiment of the invention;

35 Fig. 2 is an enlarged fragmentary sectional view taken on the line 2—2 of Fig. 1 in the direction of the arrows showing the channel members secured to the inner and outer edges of one of the annular segments and the means for holding 40 the drum in position between the heads.

Fig. 3 is a sectional view similar to Fig. 2 showing an alternate embodiment of the invention when used with a different type of drum;

45 Fig. 4 is a perspective view of one of the corrugated segments showing how the corrugations are formed to form a rectangular sheet to a semi-circular shape;

Fig. 5 is a perspective view showing schematically a set of rolls which may be used to form the 50 corrugated segments if the process is to be done by roll forming apparatus;

Fig. 6 is a partial sectional view taken on the line 6—6 of Fig. 1 in the direction of the arrows, and

55 Fig. 7 is a partial sectional view taken on the

line 7—7 of Fig. 6 in the direction of the arrows showing a modified embodiment of the structure shown in Figs. 1 and 6.

Referring now to the drawings wherein like reference characters designate the same parts throughout the several views, the head of the reel is built up of four segments 10, each of which is comprised of a rectangular sheet of metal corrugated to form a semi-circular plate having deeper corrugations at its narrower edge than at 10 its wider or outer edge. This construction will make the head segment 10 progressively stronger from its outer to its inner edge. The segments may be formed by forming rolls 9 such as those shown schematically in Fig. 5, which may be 15 driven by suitable mechanism (not shown) and which will receive a rectangular sheet between them to form corrugations in it deeper along one edge than along the other to bend the sheet into substantially arcuate form without the necessity 20 of drawing the metal. After the segments 10 have been corrugated or fluted as just described, they are welded together as shown by the heavy lines 11 (Fig. 1) to form an annular disk which 25 serves as a head of a reel. If desired, the disk may be made of a single strip of metal long enough to form the entire annulus.

After the annular corrugated disks have been formed by welding the segments 10 together, an annular channel member 12 is spot welded to the 30 inner surface of the annular disk as shown at 13 and an annular channel member 14 is spot welded to the outer surface of the annular disk as shown at 15 and 16. These point welds secure 35 the annular disk to the channel member 14 at the apex of each corrugation or spoke and to the channel member 12 at the mid point between the apexes of the corrugations or spokes. For certain types of stresses to which the reel may be subjected it is preferable to weld the annular 40 reinforcing members to the spokes at selected points rather than having a continuous weld all around the end of the spoke. The greater flexibility thus secured will add to the life of the reel when subjected to such stresses.

45 The channel member 12 has apertures 17 formed in its flanges through which bolts 18 may be passed to support a flanged drum 19 having apertures 20 therein in alignment with the apertures 17 in the channel member 12. The flanged 50 drum 19 extends between the heads and serves to space them apart a predetermined distance and is attached to both of the heads in the manner shown in Fig. 2. The bolts 18 pass through the flanges of the inner channel member 12 and 55

serve to compress and position the drum 19 on the heads. The drum is provided with a suitable aperture 21 for receiving one end of a cable to be wound thereon.

5 The contour of the corrugations or spokes as shown herein is one which has been chosen for the purpose of illustration and obviously may be varied as desired. It is preferable for convenience of manufacture and to avoid waste of material 10 that the sheets from which the corrugated annulus is made be rectangular in form. When the sheets have this form the total developed length around the inner circle of the annulus is equal to that around the outer circle. Then considering 15 the corrugations facing one side of the sheet as spokes interconnected by webs, the developed width of the metal in each spoke from the center of one web to the center of the next web at the inner end of the spoke is equal to the developed 20 width at the outer end or at any other point along the spoke.

It may be desirable in some cases to have a smooth inner surface on the reel head to prevent 25 flexible material wound thereon from binding in the corrugations and when such is the case a liner plate 60 may be welded to the corrugated portion of the head and to the outer annular channel member 14 as shown at 61 and 62.

The reel head structure of this invention lends 30 itself well to the utilization of light weight heat hardenable materials, which can be formed while in the unhardened condition and heat treated to increase their strength either in the fully assembled condition or in a partially assembled 35 condition.

In some instances it is desirable to mount reels of this type upon reel stands so that cable wound thereon may be drawn therefrom for insertion in cable conduits. This necessity of unwinding material from the reel, sometimes occurs in the field 40 and at such times the reels are rotated about their axis and the cable fed from the reel directly into conduits.

In order to facilitate the removal of material 45 from the reel there is provided a pair of spiders 22 which may be positioned adjacent the reel heads on each side of the drum. These spiders consist of radial arms 23, 24, 25 and 26 which are formed from one piece of metal and have a 50 substantially U-shaped cross section. At the junction point 27 of the arms 23, 24, 25 and 26, apertures 28 are formed to receive the rod or shaft of a reel stand about which the reel is to be rotated. The outer ends of the arms are bent 55 as shown at 30 to engage the reel heads, lugs 31 being provided on the drum to prevent axial movement of the spiders and the bent portions are provided with apertures 29 through which the bolts 18 may be passed to hold the spider in 60 place.

In the modification shown in Fig. 7 the spiders are, at the outer ends of the arms 23, 24, 25 and 26, provided with bent portions 50 having L-shaped slots 32. This construction permits the 65 bent portions of the arms to engage the inner surface of the heads and the edges of the slots to engage the bolts 18. Thus the spider 22 may be inserted in the reel and held in place by the bolts 18 and the insertion or removal of the 70 spiders may be effected with great ease. The spiders shown herein are similar to those disclosed in U. S. Patent 1,911,427 to A. A. Bureau.

Referring to Fig. 3 wherein a modified embodiment of the invention is shown, the numeral 48 75 indicates a straight drum not having flanges

formed thereon which may be used. In this embodiment of the invention the annular member 12 is not used and the annular disk formed by the segments 10 is spot welded to the peripheral surface of the drum 40 at points 41 which are at the mid points between the apexes of the corrugations in the segments 10. With this type of drum construction the spiders may be bent as shown at 42 and bolted to the drum as shown at 43.

10 Although the invention has been described specifically, it is to be understood that it is not limited except by the scope of the appended claims.

15 What is claimed is:

1. A reel head including a disk formed from sheet material corrugated to form an annulus with the corrugations therein having substantial depth at right angles to the plane of the annulus from edge to edge of the sheet and being progressively deeper from one edge of the material to the other, an annular reinforcing member welded only adjacent the apexes of the corrugations at the outer edge of the annulus, and an annular reinforcing member welded to the inner 25 edge of the annulus only adjacent the mid points between the apexes of the corrugations.

2. A reel including spaced heads, and a flanged drum, said heads comprising a plurality of arcuately shaped segments each formed from a rectangular sheet of metal and corrugated irregularly to form them to the segment of an annulus, the segments being welded together to form said annulus, outer circular channel members having their flanges extending inwardly and welded to 30 the outer apexes of the corrugations in the heads, inner circular channel members having their flanges extending inwardly and having their webs welded to the mid point between the apexes of the corrugations in the heads, and a plurality of bolts 40 extending between the heads and extending through apertures in the flanges of the drum and through apertures in the flanges of the inner circular channel members to secure the heads and drum in place.

45 3. A method of forming a reel head comprising undulatingly corrugating rectangular sheet material and making the corrugations with a substantial depth at both edges of the sheet and at right angles to the plane of the material before 50 it is corrugated and deeper along one edge of the material than along the opposite edge to reduce the overall linear dimension of the material at one edge relative to the overall linear dimension at the other edge thereby to form an annulus 55 thicker at its inner circular edge than at its outer circular edge, and securing reinforcing members to the inner and outer edges of the annulus by point welding the apexes of the corrugations to the outer reinforcing member, and by point welding the mid-points between the apexes of the corrugations to the inner reinforcing member.

4. A reel head including a disk formed from sheet material corrugated to form an annulus with the corrugations therein formed radially at 65 right angles to the plane of the annulus from edge to edge of the sheet and having substantial depth at both edges but deeper at one edge than at the other, and an annular reinforcing member welded to the outer edge of the annulus at predetermined spots along the edge of the corrugations to permit, under normal strains, a small amount of relative movement between the portions of the head and reinforcing member which are not welded together.

5. A method of forming a reel head comprising undulatingly corrugating rectangular sheet material and making the corrugations with a substantial depth at both edges at right angles to the plane of the uncorrugated sheet and deeper along one edge of the material than along the opposite edge to reduce the overall linear dimension of the material at one edge relative to the overall linear dimension at the other edge there-

by to form an annulus thicker at its inner circular edge than at its outer circular edge, and securing reinforcing members to the inner and outer edges of the annulus by point welding portions of the edges of the corrugations to the outer reinforcing member and by point welding portions of the edges of the corrugations to the inner reinforcing member.
